ROCK DRILLING MECHANISM

George W. Hulshizer, Stewartsville, N. J., assignee to Ingersoll-Rand Company, Jersey City, N. J., a corporation of New Jersey

Application June 20, 1932, Serial No. 618,269

5. Claims. (Cl. 121—5)

This invention relates to rock drilling mechanism, but more particularly to a feeding device for fluid actuated rock drills of the hand held type, such as coal picks and the like.

5 One object of the invention is to maintain a uniform feeding pressure on the working implement actuated by the rock drill.

Another object is to enable a rock drill equipped with a feeding device and normally employed for horizontal drilling to be conveniently rotated by the operator in order to constantly change the position of the working implement with respect to the work.

15 A further object is to enable the feeding device to be quickly and securely attached to the rock drill.

Other objects will be in part obvious and in part pointed out hereinafter.

In the accompanying drawings illustrating the 20 invention and in which similar reference characters refer to similar parts.

Figure 1 is a longitudinal side elevation of a 25 rock drilling mechanism constructed in accordance with the practice of the invention and having a supporting device which is partly broken away.

Figure 2 is a longitudinal sectional elevation of the feeding mechanism.

Figures 3 and 4 are transverse views taken 30 through Figures 1 and 2 respectively on the lines 3—3 and 4—4 looking in the directions indicated by the arrows, and

Figures 5 and 6 are sectional plan views taken 35 through Figure 2 on the lines 5—5 and 6—6, respectively, looking in the directions indicated by the arrows.

Referring more particularly to the drawings, the drilling mechanism which is designated in general by A comprises a motor B and a feeding mechanism C to actuate the motor with respect 40 to a mounting D whereby the drilling mechanism is supported.

The motor B, which is illustrated as being in the form of a coal pick of the fluid actuated percussive type, is provided with a working implement E for drilling holes in the rock F. The working implement E may be of polygonal shape to interlock with the motor or portions thereof for preventing relative rotary movement between 45 the working implement and the motor.

The feeding mechanism C, constructed in accordance with the practice of the invention, comprises a feeding cylinder G having a piston chamber H for the accommodation of a reciprocable 50 piston J, of which the rear and front ends con-

stitute pressure areas K and L, respectively, against which pressure fluid may act for actuating the piston J. A piston rod O on the piston J extends through a head P and a packing device Q at the front end of the cylinder G, and the head P and the packing device Q are retained in the correct assembled position by means of a cap R threaded on the end of the cylinder G.

At the rear end of the cylinder G is an enclosure S for that end of the piston chamber H and into which it may extend with one end. The enclosure may be suitably secured to the cylinder G, as for instance by welding as indicated at T, and has a reduced extension U which extends into a recess V of a back head W secured to the cylinder G by bolts X disposed on opposite sides of the cylinder and threaded at one end into a boss Y on the cylinder G.

Included as a part of the back head W is a valve chest Z having a valve chamber b for the 75 accommodation of a rotary throttle valve c having a lever d whereby it may be manipulated. Within the throttle valve c is a chamber e into which pressure fluid may be constantly introduced from a source of supply, and in the wall of the throttle valve are a pair of ports f and g through which pressure fluid passes from the chamber e for supplying the ends of the piston chamber H.

The ports f and g are so arranged that in one 85 limiting position of the throttle valve the port g registers with a passage h in the back head W and the enclosure S and opening into the rear end of the piston chamber H. In another limiting position of the throttle valve the port f registers with a passage i which opens into the recess V and of which the rear end of the extension U forms a bounding surface.

Within the extension U is a tube k that extends 90 through the piston J into the rod O and preferably to a point near the front end of the cylinder G so that when the port f registers with the passage i direct communication will be established 95 between the chamber e and the interior of the rod O. In the wall of the rod O, and preferably adjacent the pressure area L, is a port o through which pressure fluid passes from the interior of the rod O into the front end of the piston chamber H.

To the end that the pressure fluid employed 100 for actuating the piston J may be conveniently exhausted from the ends of the piston chamber H and through the same passages through which the admission of pressure fluid is effected to the ends of the piston chamber, the throttle valve c 110

is provided with a pair of longitudinally extending grooves *p* and *q* adapted to register with the passages *h* and *j* respectively. The grooves *p* and *q* are joined at one end by an annular groove *r* in the periphery of the throttle valve *c* and the said groove *r* may be in constant communication with an exhaust port *s* in the valve chest *Z*.

Preferably the pressure fluid employed for actuating the motor *B* also passes through the throttle valve *c*, thus necessitating only a single connection between the source of pressure fluid supply and the drilling mechanism. The throttle valve *c* is accordingly provided with a port *t* through which pressure fluid flows in the open

position of the throttle valve *c* to a passage *u* leading to a chamber *v* also in the back head *W* and having a seating surface *w* at one end for the accommodation of a poppet valve *x* which is normally maintained upon the seating surface *w* by a spring *y* in the chamber *v*. From the chamber *v* leads a passage *z* to which is connected one end of a hose *2* and of which the other end is connected to the motor *B*.

In order to guide, rotate and adjust the drilling mechanism with respect to the work the back head *W* is provided with a pair of grip members *3* which are secured to the back head by a rod or bolt *4*. The bolt *4* extends through the grip members *3* and the back head *W* and has a nut *5* threaded thereon for clamping the grip members *3* securely to the back head. Mounted pivotally upon one of the grip members *3* is a lever *6* which acts against a stem *7* of the valve *x* for opening said valve.

To the end that the motor *B* may be supported by the piston rod *O* a cradle *8* is threaded to the outer projecting end of the piston rod and clamped securely thereto by a pinch bolt *9*. On the portion of the cradle *8* adjacent the end of the rod *O* is a slot *10* to accommodate a rear extremity of the motor *B*, as for instance a handle *11*.

An arm portion *12* of the cradle may be shaped to conform substantially to the shape of the motor *B* and extends forwardly along the motor and terminates in a half-bearing *13* which may be an integral portion of the cradle. In order to clamp the front extremity of the motor *B* securely to the cradle *8* a bearing cap *14* is connected with one end to the bearing *13*, as by means of a pivot *15*, and to the opposite end of the bearing *13* is pivoted an eye-bolt *16* adapted to lie in a slot *17* in the bearing cap *14* and having a nut *18* for clamping the half-bearing *13* and the bearing cap *14* securely to the motor *B*.

Means are provided for preventing deflection of the piston rod *O*, particularly in the extended position of said piston rod. The means employed for this purpose comprises a support rod *19* which is affixed with its front end to a lug *20* on the portion of the cradle *8* adjacent the end of the piston rod *O*. The rod *19* extends slidably through an aperture *21* in the boss *Y* and is threadedly connected with its rear end to a sleeve *22* slidable on the feeding cylinder *G*. The sleeve *22* is, in the present instance, provided with apertures *23* to receive the bolts *X* so that the sleeve *22* and the feeding cylinder *G* will be interlocked against relative rotary movement.

The mounting *D* whereby the drilling mechanism *A* is supported comprises a bearing member *24* wherein the feeding cylinder *G* is freely rotatable. One end of the bearing member *24* seats, in the present instance, against the boss *Y* and the other end of the bearing member against a collar

25 that encircles the feeding cylinder *G* and to which the collar is clamped by means of a bolt *26*. Preferably the bolt *26* is engaged by a notch *27* in the surface of the feeding cylinder to prevent longitudinal movement of the collar *25* thereon.

In order that the drilling mechanism may be conveniently oscillated in a horizontal plane the bearing member *24* is provided with a shaft or spindle *28* journaled in a bearing *29* which itself may be rotatably mounted upon a horizontal bar *30*. The bar *30* may be conveniently supported by crossheads *31* having adjustable legs *32* whereby the height of the mounting and the drilling mechanism may be varied.

The operation of the device is as follows: Let it be assumed that the piston *J* and therefore the motor *B* lie in their rearmost limiting positions and that it be desired to actuate the working implement *E* into the work. If then the throttle valve *c* is rotated to place the port *g* in registry with the passage *h* pressure fluid will be admitted into the rear end of the piston chamber *H* to act against the pressure area *K* for moving the motor *B* towards the rock *F*. In this position of the throttle valve *c* pressure fluid is also admitted into the chamber *v* so that by opening the valve *x* pressure fluid will flow through the hose *2* to the motor *B* where it may be distributed to the percussive element by a suitable distributing valve (not shown).

During the time the throttle valve *c* occupies the position described the groove *q* communicates with the passage *j* and the exhaust port *s* so that the front end of the piston chamber *H* will be in direct communication with the atmosphere.

Upon completion of the drill hole *F*, or after the working implement *E* has penetrated the work to the limit of its extent, the throttle valve *c* is rocked to its other limiting position for retracting the motor from the work. In this position of the throttle valve the port *f* registers with the passage *j* and the groove *p* with the passage *h*. The pressure fluid previously employed for actuating the motor towards the work will then be exhausted from the rear end of the piston chamber and pressure fluid flows through the port *f*, the passage *j* and the tube *k* into the piston rod *O*, thence through the port *o* into the front end of the piston chamber *H* to act against the pressure area *L* for moving the piston *J* and the motor *B* rearwardly.

During the operation of drilling the position of the working implement *E* upon the work may be constantly changed by rotating or oscillating the drilling mechanism *A* in the bearing member *24*. This may be conveniently accomplished by means of the grip members *3* which may be rocked to and fro and the entire drilling mechanism *A* will follow the movement of the grip members.

I claim:

1. In a rock drilling mechanism, a fluid actuated motor adapted to actuate a working implement, a feeding cylinder, a fluid actuated piston in the feeding cylinder, a piston rod on the piston, means extending forwardly of the rod for connecting the rod to the motor, a support rod arranged exteriorly of the feeding cylinder and being connected to the piston rod and the said means for preventing deflection of the piston rod, and means for preventing relative rotation between the feeding cylinder and the piston.

2. In a rock drilling mechanism, a fluid actuated motor adapted to actuate a working implement, a feeding cylinder, a fluid actuated piston in the feeding cylinder, a piston rod on the piston, a cradle on the piston rod extending forwardly

- thereof to receive and support the motor, a support rod exteriorly of the feeding cylinder connected at one end to the cradle and having its other end connected slidably to the feeding cylinder, and means on the feeding cylinder engaging the support rod to prevent relative rotation between the feeding cylinder and the piston. 6 80
3. In a rock drilling mechanism, a fluid actuated motor adapted to actuate a working implement, a feeding cylinder, a fluid actuated piston in the feeding cylinder, a piston rod on the piston, a cradle on the piston rod extending forwardly of the rod to receive and support the motor, a support rod exteriorly of the feeding cylinder and being connected with one end to the cradle for preventing deflection of the piston rod, a sleeve affixed to the other end of the support rod and being slidable on the feeding cylinder, and a boss on the feeding cylinder, engaging the support rod 10 to prevent rotation of the feeding cylinder with respect to the piston. 15 90
4. In a rock drilling mechanism, a fluid actuated motor adapted to actuate a working implement, a bearing member, a feeding cylinder rotatable within the bearing member and having a boss, a head for the feeding cylinder, bolts in the boss and the head for securing the head to the feeding cylinder, a piston in the feeding cylinder and having a piston rod, a cradle carried by 20 the piston rod to receive and support the motor, 25 95
5. In a drilling mechanism, the combination of a fluid actuated motor adapted to actuate a working implement, a bearing member, a feeding cylinder supported by the bearing member and being rotatable therein, a boss on the cylinder, front and back heads for the feeding cylinder, bolts in the boss for securing the back head to the feeding cylinder, a piston in the feeding cylinder having a rod, a cradle on the rod to receive and support the motor, a support rod slidable through the boss and being connected with one end to the cradle, a sleeve on the other end of the support rod and being slidable on the bolts and the feeding cylinder, means in the back head for selectively controlling the admission and exhaust of pressure fluid to and from the ends of the feeding cylinder, 100 and a handle in the back head for rotating the entire drilling mechanism with respect to the bearing member. 105
